RADIO APPARATUS

Charles J. Hirsch, New Rochelle, N. Y., assignor
to Thomas A. Edison, Incorporated, West
Orange, N. J., a corporation of New Jersey

Application August 26, 1930, Serial No. 477,853

5 Claims. (Cl. 178—44)

This invention relates to radio apparatus and more particularly to radio receiving apparatus intended to cover relatively wide ranges of frequency.

5 It is an object of this invention to provide apparatus of the class described which will operate to select signals within a predetermined band of frequencies and in which the particular band of frequencies to be received may be shifted as desired.

10 It is a further object of this invention to provide apparatus of the class described which does not require a change of coils or the like when it is desired to change the band to be covered.

15 It is a further object of this invention to provide radio receiving apparatus which is particularly adapted to receive stations operating within the broadcast spectrum and which may be adjusted to receive signals of either higher or lower

20 frequencies. It is a further object of this invention to provide apparatus of the class described in which the apparatus may be converted from a broadcast receiver to receive frequencies higher or 25 lower than the broadcast frequencies without the insertion or removal of special coils or the like.

Still other objects and advantages of my invention will be apparent from the specification.

30 The features of novelty which I believe to be characteristic of my invention are set forth with particularity in the appended claims. My invention itself, however, both as to its fundamental principles and as to its particular embodiments, will best be understood by reference to the specification and accompanying drawing, in which

Figs. 1 and 2 illustrate the type of circuit utilized to provide a shift in the reception band.

40 Fig. 3 shows one form of receiving apparatus in accordance with my invention.

Fig. 4 shows a modified form of receiving apparatus in accordance with my invention, and

Fig. 5 shows still another form of receiving apparatus in accordance with my invention.

In the various figures, like reference numerals indicate like parts.

At the present time the radio broadcasting frequency band covers approximately the range between 550 to 1500 kilocycles and all broadcast receiving apparatus is particularly designed so as to cover this band. However, matters of interest to the public are also transmitted on other frequencies, for example at very much higher frequencies, as in the so-called short waves.

55 I am aware that it has been proposed in the past to utilize broadcast receiving apparatus for receiving either higher or lower frequencies outside of the broadcast range by removing the 60 transformers or coils and substituting different

transformers or coils, particularly designed to cover other ranges. This procedure is open to many objections, among which may be mentioned the necessity of having on hand additional sets of transformers or coils which may be substituted for those in use, the difficulty of arranging the apparatus so that it is mechanically stable while at the same time the transformers or coils are accessible so as to be easily removed and replaced, the difficulty of maintaining electrical efficiency particularly due to the tendency of the contacts on the coils or transformers and associated apparatus to corrode or oxidize with resultant decrease in efficiency of the receiver, and the additional cost involved in providing the extra coils or the like, and in arranging the apparatus to provide for the substitution of coils.

In accordance with one aspect of my invention, I eliminate the necessity for changing transformers or coils when it is desired to change the band of frequencies to be received, by utilizing coupled circuits and controlling the coupling between the circuits in such a manner as to shift the band to be received. The coupling between the circuits may be constituted by capacity, self-inductance, or mutual inductance.

Referring now particularly to Fig. 1, it will be seen that inductance L_1 , capacity C_1 and C_m constitute one tuned circuit. Inductance L_2 , capacity C_2 and capacity C_m constitute a second tuned circuit. These circuits are coupled through the capacity C_m which is common to the two circuits. It is known that under certain conditions such coupled circuits give rise to peaks occurring at different frequencies.

If the two circuits have their constants so chosen as to be separately resonant to the same frequency, which is represented as ω_0 , for example, if $L_1=L_2$ and $C_1=C_2$, neglecting the resistance of the circuits, there will be two peaks or frequencies of maximum response, one of which

$$\omega_1 = \omega_0 \cdot \sqrt{1+K} \quad (1)$$

and the other of which,

$$\omega_2 = \omega_0 \cdot \sqrt{1-K} \quad (2)$$

where K is the coefficient of coupling.

In this case

$$\omega_0 = \sqrt{\frac{C_1 + C_m}{L_1 C_1 C_m}} \quad (3)$$

and

$$K = \frac{C_1}{C_1 + C_m} \quad (4)$$

Substituting in Equation (1) I obtain

$$\omega_1 = \sqrt{\frac{2}{L_1 C_m} + \frac{1}{L_1 C_1}} \quad (5)$$

If L_1 and C_1 are already fixed by the requirement of one frequency band, a suitable value of

C_m can be chosen to cover another band. A suitable value of C_1 can be chosen if L_1 and C_m are fixed.

The circuit will also respond to a frequency determined by Equation (2) which can be re-written as

$$\omega_2 = \frac{1}{\sqrt{L \cdot C}} \quad (6)$$

10 (obtained by the substitution in Equation (2) of the values of ω_0 and K given by Equation (3) and (4).

If we are interested only in ω_1 and vary the tuning by varying C_m it will be seen that ω_2 is independent of the value of C_m and can be removed by a simple filter, since it does not change with variation in C_m .

This happens because the values of ω_0 and K are both affected simultaneously by changes in the value of C_m , in such a manner that the value of ω_2 is left unchanged by variations in the value of C_m .

Referring now more particularly to the circuit shown in Fig. 2, which is generally similar to the circuit of Fig. 1, except that the coupling is now obtained by a common self-inductance, L_m instead of capacity C_m , this circuit is responsive to two frequencies as before, but the frequencies are now given by the following:

$$30 \quad \omega_3 = \frac{\omega_0}{\sqrt{1-K}} \quad (7)$$

and

$$35 \quad \omega_4 = \frac{\omega_0}{\sqrt{1+K}} \quad (8)$$

and

$$40 \quad \omega_0 = \frac{1}{\sqrt{C_1(L_1+L_m)}} \quad (9)$$

and

$$45 \quad K = \frac{L_m}{\sqrt{L_1+L_m}} \quad (10)$$

Substituting these values in Equations (7) and (8) I obtain

$$50 \quad \omega_3 = \frac{1}{\sqrt{L_1 \cdot C}} \quad (11)$$

and

$$55 \quad \omega_4 = \frac{1}{\sqrt{C_1(L_1+2L_m)}} \quad (12)$$

Thus the circuit may be selective to a frequency determined by L and C_1 alone, and in operation the band to be received may be controlled by varying the value of the capacity C_m or the inductance L_m , after which stations within the band may be selected by varying the capacities C_1 and C_2 .

The formulae (7) and (8) developed in connection with Fig. 2 above apply also where the coupling between the circuits is of the type shown in Fig. 3 (i. e., by mutual inductance instead of a common self-inductance), in which case it will be found that

$$60 \quad \omega_0 = \frac{1}{\sqrt{L_1 C_1}} \quad (13)$$

where, for example, L_1 is the self-inductance of coil 4 and C_1 the capacity of condenser 3 and

$$70 \quad K = \frac{M}{\sqrt{L_1 L_2}} \quad (14)$$

where M is the mutual inductance between coils 4 and 5 and L_1 and L_2 are respectively the self-inductances of coils 4 and 5.

75 It will be noted in this case that since the

value of K may be altered without affecting the value of ω_0 , both ω_3 and ω_4 will vary with changing values of K .

In general, it may be stated that whatever the nature of the coupling between the circuits, as the coupling is made less, ω_1 and ω_2 , the two maximum response frequencies of the system approach each other and approach the resonant frequency of the individual tuned circuits, and conversely as the coupling is tightened, the greater the difference between them.

From the foregoing mathematics we may tabulate the results for comparative purposes. In making this tabulation it should be borne in mind that in the case of the circuit shown in Fig. 3 where the coupling is by mutual inductance and not by a common self-inductance, the tabulation may be simplified by the use of an additional formula, which is

$$95 \quad L_1 = L_0 + L_m$$

where L_1 is the total inductance in the individual circuit and is, of course, made up of the two components L_0 , the self inductance of the circuit, considered separately, plus L_m , which is the mutual inductance or the inductance common to the two circuits by reason of the flux which interlinks the primary and secondary coils.

In the following table the first column of formulae represents the value of ω_2 for the three circuits shown respectively in Figs. 1, 2 and 3; the center column the formulae for ω_0 for the same three cases, and the third column the formulae for ω_1 for the same three cases. The figures in parenthesis refer to the formulae already derived.

	ω_2 (6)	ω_0 (3)	ω_1 (5)
Fig. 1	$\sqrt{\frac{1}{L_1 C_1}}$	$\sqrt{\frac{1}{L_1 C_1} + \frac{1}{L_1 C_m}}$	$\sqrt{\frac{1}{L_1 C_1} + \frac{2}{L_1 C_m}}$
Fig. 2	$\frac{1}{\sqrt{C_1(L_1+2L_m)}}$	$\frac{1}{\sqrt{C_1(L_1+L_m)}}$	$\frac{1}{\sqrt{C_1 L_1}}$
Fig. 3	$\frac{1}{\sqrt{C_1(L_0+L_m)}}$	$\frac{1}{\sqrt{C_1 L_0}}$	$\frac{1}{\sqrt{C_1(L_0-L_m)}}$

The formulae in the above table, in some cases, are in slightly different form from those indicated by the reference numerals, but mathematically they are identical.

From this it will be seen that in the case of the circuit shown in Fig. 1, when the coupling capacity is varied ω_2 remains constant, ω_0 approaches infinity as a limit and ω_1 also approaches infinity as a limit but ω_1 is always greater than ω_0 .

For the circuit shown in Fig. 2, as the coupling between the circuits is increased, ω_1 remains constant, ω_0 approaches zero as a limit and ω_2 approaches zero as a limit, but ω_2 is always less than ω_1 .

For the circuit of Fig. 3, it will be seen that as the coupling between the circuits is tightened ω_0 remains unchanged, ω_2 decreases, approaching 0.7 ω_0 as a limit, and ω_1 increases approaching infinity as a limit. It will be understood that the limiting case is represented by the condition where the coefficient of coupling is equal to one.

It should also be remembered that of these three frequencies ω_0 , ω_1 and ω_2 , only ω_1 and ω_2 are actual response or "hearing frequencies". ω_0 from its definition, is a "hearing frequency" only when the coupling is extremely loose ap-

proaching zero, in which case as a practical matter ω_1 and ω_2 , which are the "hearing frequencies" lie very close together. In practice this is the condition which obtains when the receiver is 5 tuned to a broadcast frequency, in which case ω_1 and ω_2 might differ by say 5 kilocycles and ω_0 lying between them would also be heard.

Referring now more particularly to Fig. 3 in which I have shown diagrammatically one form 10 of radio receiver embodying this invention, there is provided an antenna 1 and condenser 2. The first resonant circuit comprises condenser 3, and coil 4, and the first resonant circuit is coupled to a second resonant circuit comprising condenser 15 6 and coil 5 through the medium of coils 4 and 5, the coupling between which is made variable in any suitable way. The lower ends 20 of the coils 4 and 5 and the corresponding plates of the condensers 3 and 6 may be connected together and to ground as shown. The output of 25 the second circuit may be amplified to the amount desired by an amplifier 7 and passed through any suitable type of filter, the output of which may be detected by any suitable detector 9 and supplied to any suitable indicating device such as receivers 10.

If the constants of condensers 3 and 6 and coils 30 4 and 5 are the same and are so chosen that the circuits separately are tuned to 550 kilocycles, with the condensers set for maximum capacity, the combination comprising condenser 3 and coil 35 4 and condenser 6 and coil 5 coupled through the mutual inductance of coils 4 and 5 will have peaks occurring at two frequencies given by

$$550$$

$$\sqrt{1+K}$$

and

$$550$$

$$\sqrt{1-K}$$

Broadcast receivers utilizing coupled circuits at the present time usually have a coupling of 40 about 0.01 so that the first peak will be seen to occur at 553 kilocycles and the second peak at 45 547 kilocycles. Thus the two peaks occur quite close together.

If without altering either the coil or the condenser in either circuit the coupling be increased to 0.96 then one peak will occur at 2750 kilocycles, the other peak at 393 kilocycles. Here, however, a difference appears between the circuits shown in Figs. 1 and 2, where the coupling is by common capacity and common self-inductance respectively, and the circuit shown in Fig. 3, where the 50 coupling is by mutual inductance. It should be noted that in the case of the circuits in Figs. 1 and 2 variation of the common condenser C_m or of the common inductance L_m will cause a variation of the frequency ω_0 to which each of 55 the circuits when considered separately is tuned, whereas in the case of Fig. 3 the coupling being mutual inductance only may be varied without changing ω_0 . Variation of the mutual inductance only without changing the self-inductance 60 of either of the coils coupled through a mutual inductance, as is well known, may be obtained in a number of known ways, such for example, as varying the distance between the coupled coils or varying the relative direction of their axes as 65 70 by rotating one or the other. If it is desired to receive stations in the neighborhood of 2750 kilocycles, signals in the neighborhood of 393 kilocycles, if present, will be undesired and may be removed by the filter 8 constructed in any 75 known way to remove frequencies in this neighbor-

hood. This filter may advantageously be a so-called "high-pass" type suppressing frequencies below the lowest frequency desired to be received, which in this instance would be 550 kilocycles. Of course it will be understood that if there are no stations transmitting in the neighborhood of this undesired frequency the filter may be omitted and it will be understood that by proper selection of the constants the second peak may be made to fall at any desired point, within limits.

If the coupling be made still tighter, for example, 0.99 the upper peak will occur at a still higher frequency, in this case 5500 kilocycles. Thus it will be seen that without changing the coils or condensers, the upper peak can be shifted from 550 kilocycles to 5500 kilocycles while still keeping each of the circuits respectively comprising condenser 3 and coil 4, and condenser 6 and coil 5, when considered separately, tuned to 550 kilocycles, that is with the variable condensers 3 and 6 set to their maximum value. If the variable condensers are set to their minimum value so that the resonant circuits would be separately tuned to 1500 kilocycles, then with a 100 coupling of 0.99 the upper frequency will become 15,000 kilocycles.

Tuning may be accomplished either by variation of the coupling coefficient to the proper value, as by varying the coupling between coils 105 4 and 5 without any other change or it may be accomplished by changing the coefficient of coupling in steps to give an approximate tuning and by variation of the tuning condensers 3 and 6 to give the final selection of the desired frequency. 110

In cases where it is desired to obtain very high coupling between the two circuits it may be difficult to obtain sufficiently close coupling merely by bringing coils 4 and 5 together, and in this case additional inductances 11 and 12 may be 115 inserted as shown in Fig. 4 and coils 4 and 5 replaced by inductance 13. The inductance 13 may be the usual tuning inductance of a broadcast receiver and may have a value of 200 mhs. For example, it may be either coil 4 or coil 5 120 alone. Then if the inductances 11 and 12 are made to have a value of 2 mhs. the coefficient of coupling will be

$$\frac{200}{202} = 0.99.$$

125

Referring now more particularly to Fig. 5, I have shown a radio receiver embodying alternate steps of selection and amplification repeatedly. In this instance the first pair of selecting 130 circuits comprises inductances 21 and 25, tuning condensers 22 and 24 and coupling condensers 23, coil 21 being coupled to coil 20 in circuit with antenna 1. The output of the first pair of circuits may be amplified by any suitable amplifier 135 such, for example, as vacuum tube having an anode 28, cathode 26 and control electrode 27, anode potential being supplied by a suitable source 29. Since the construction and operation of amplifiers is well known in the art and forms, 140 per se, no part of the present invention, the same is not described in detail.

The second pair of selecting circuits is made up by inductances 31 and 35, tuning condensers 32 and 34 and coupling condenser 33. The coil 31 145 is coupled to coil 30 connected to the anode 28 of the previous amplifier. The second pair of selecting circuits is similar to the first pair already described and is therefore not described in detail. Similarly the output of the second pair 150

of selecting circuits may be amplified by a second amplifier comprising anode 38, cathode 36 and control electrode 37, the anode being energized from a suitable source of potential 39.

5 The output of the second amplifier may be still further selected and amplified if desired, or amplified without further selection or further selected without further amplification. In the arrangement shown I have indicated a filter following the output of the second amplifier, said filter comprising condensers 41 and 43 and inductances 40, 42 and 44, having constants so chosen as to bypass any undesired frequencies and more particularly the low frequency peak arising 10 from the action of the coupled circuits as already described. The amplified and selected currents may then be detected in any suitable manner as, for example, by a vacuum tube detector comprising an anode 49, cathode 47 and control electrode 48 to which is connected grid condensers 45 and grid leak 46. A suitable source of potential 50 is provided for energizing the anode 49 and any suitable indicator such as receivers 10 may be connected thereto, it being understood of course 15 that the signals may be further amplified after being detected before being supplied to the indicator.

The variable tuning condensers 22, 24, 32 and 34 may be all connected together and to a single operating means if desired, and similarly the variable coupling condensers 23 and 33 may be connected together and to a single operating means. If it is desired to use the apparatus as a broadcast receiver, the coupling condensers 23 and 33 20 will be set to such a value that the coupling between the coupled resonant circuits is of the order of 1%. The desired broadcast signal may then be tuned in the usual way. If a frequency above the broadcast frequency is desired, condensers 23 and 33 are then adjusted to give tighter coupling, as already described. Selection of the signal may then be made, either by variation 25 of coupling or by variation of the tuning condensers.

45 While I have shown and described my invention with particular application to radio frequency currents, it will be understood that it is not limited thereto, but is capable of use in many other arrangements wherein it is desired to select or separate currents of one frequency or band of frequencies from those of another and that modifications and changes may be made without departing from the spirit and scope of my invention, as 50 will be understood by those skilled in the art.

55 I claim:

1. Radio receiving apparatus comprising, in combination, a signal collecting circuit, a selecting circuit, and a circuit to be supplied with selected signals, said circuits being arranged in cascade relation, and said selecting circuit comprising a pair of resonant circuits, each separately tunable from 550 to 1500 kilocycles and having a common coupling reactance variable with respect to the reactances of said resonant circuits over such a range that said selecting circuit may be caused to respond to two frequencies simultaneously one of which is more than 1500 kilocycles and the other of which is less than 550 kilocycles.

2. Radio receiving apparatus comprising, in combination, a signal collecting circuit, a selecting circuit, a circuit to be supplied with selected signals, and a circuit for suppressing signals having 75 a frequency below a predetermined value, said

circuits being arranged in cascade relation, and said selecting circuit comprising a pair of resonant circuits, each separately tunable over only a portion of the desired frequency spectrum, and having a common coupling reactance of such value 80 relative to the reactances of said resonant circuits that the said selecting circuit may be caused to respond to two frequencies, one of which lies below the frequency of said suppressing circuit.

3. Radio apparatus for receiving signals of a desired frequency lying within an extremely wide band of frequencies, comprising, in combination, a signal collector, a signal selecting circuit, and a circuit to be supplied with selected signals, said signal selecting circuit comprising a pair of similar resonant circuits, each tunable alone over the same predetermined frequency band considerably smaller than the total band to be covered by said receiving apparatus, said circuits being coupled together by a common variable reactance, 95 the range of variability of said reactance being so chosen with respect to the constants of said circuits that the coupling between them may be varied from extremely loose to extremely tight, whereby the two response frequencies of said coupled circuits may be selectively caused to occur either substantially together and inseparable, or widely displaced and easily separable, and means for suppressing one of said response frequencies when widely displaced from 100 the other.

4. Radio apparatus for receiving signals of a desired frequency lying within an extremely wide band of frequencies, comprising, in combination, a signal collector, a signal selecting circuit, a circuit to be supplied with selected signals, and a circuit for suppressing signals lying on one side of a predetermined frequency, said signal selecting circuit comprising a pair of similar resonant circuits, each tunable alone over the same frequency band, which band is smaller than the total band of frequencies from which reception is desired, said circuits being coupled together by a common variable reactance, the range of variability of said reactance being so chosen with respect to the constants of said resonant circuits that the coupling between them may be varied from extremely loose to extremely tight, whereby the two response frequencies of said coupled circuits may be selectively caused to occur either 110 substantially together and substantially inseparable, or widely displaced and easily separable, with one of them falling within the range which is suppressed by said suppressing circuit.

5. Radio apparatus for receiving signals of a desired frequency lying within an extremely wide band of frequencies, comprising, in combination, a signal collector, a signal selecting circuit, a circuit for suppressing signals of less than a predetermined frequency, said signal selecting circuit comprising a pair of similar resonant circuits, each tunable alone over a band of frequencies substantially narrower than the extremely wide band to be covered by said radio apparatus, said circuits being coupled together by a common reactance and means for varying the coupling between said circuits from extremely loose to extremely tight, whereby the two response frequencies of said coupling system may be selectively caused to occur substantially together, 135 where they are substantially inseparable, or widely spaced and readily separable, with the lower of them falling below the range of frequencies suppressible by said suppressing circuit.
